AIR CONDITIONING APPARATUS

Robert L. Sites, South Orange, N. J., assignor, by
mesne assignments, to Air Devices Corporation,
Chicago, Ill., a corporation of Delaware

Application July 6, 1933, Serial No. 679,191
Renewed November 29, 1935

5 Claims. (Cl. 62—129)

This invention relates to air conditioning apparatus of the type including means for dehumidifying and cooling air, and has for its object an arrangement whereby the apparatus may be separated into two units, widely spaced apart in a building, one of which units comprises a refrigerating unit for cooling water which is piped to the other unit which comprises means actuated from the refrigerated water line for absorbing 10 heat and humidity from the air, and wherein the excess moisture condensed from the air in the conditioning unit may be eliminated from the system without the use of any connection to the conditioning unit other than the refrigerated water line from the refrigerator unit.

To state the present invention in a somewhat different manner, it proposes, in an air conditioning system, to eliminate water of condensation therefrom at the refrigerating portion of the 20 mechanism.

The present invention is particularly adapted for use in connection with a conditioning system which may be termed an "open system", i. e., wherein there is a break in the refrigerated 25 water line at which break the refrigerated water is sprayed into a current of air being passed through the system, and which sprayed water is collected in an open pan and returned to the refrigerating mechanism. The invention safe- 30 guards against the overflowing of the water from the open pan while at the same time eliminating excess moisture from the system, without the use of a drain connected to the open pan.

More specifically, the present invention provides for disposing of water condensate at a point 35 between a refrigerating reservoir and a delivery line for carrying the refrigerated water to the conditioning unit.

The present invention further proposes to provide a system in which the maintenance of proper water levels in the collecting pan of the conditioning unit and in the refrigerating reservoir of the refrigerating unit during normal operation is governed by the building up of a certain amount 45 of pressure in the refrigerating reservoir and balancing this pressure against the resistance of the outlet at the spray in the conditioning unit and of the delivery line connecting the reservoir to the outlet.

50 My invention utilizes this pressure which is built up in the delivery line, for the control of an escape valve which eliminates the excess moisture.

With these and other objects in view my invention consists in the construction and ar-

angement of the various parts of the invention whereby the objects contemplated are attained as hereinafter more fully set forth, pointed out in my claims and described in the accompanying drawing which is a diagram of a conditioning system embodying the invention. 5

I have used the reference characters A and B to indicate respectively the conditioning and refrigerating units of the system. The conditioning unit A may be of the general construction illustrated in the application of Frederick Riebel, Jr. and Lachlan W. Child, Serial No. 680,439, filed July 14, 1933.

It comprises, among other elements, a water pan 10 in which is mounted a float valve 11 controlling the delivery of water to a spray impeller 12. The float valve 11 is entirely closed at the level indicated by the full line 13.

The refrigerating unit B may be of any standard compressor type refrigerator, including a reservoir 15 into which water from the return connection 14 is pumped through the return line 16, 17. The pipe 16 connects the return connection 14 to the pump 18 and the pipe 17 connects the pump 18 to the reservoir 15. 20

The water is delivered from the reservoir 15 under a slight pressure head which may vary according to the compression of an air cushion 19 in the top of the reservoir 15, to a delivery line 20, leading to the connection 21 of the float valve 11 of the conditioning unit A. 25

The refrigerator is provided with a conventional compressor 22 operated by a motor, compressing a refrigerating gas into a coil 24 which delivers the refrigerant into a tank 25 from which it is delivered through a tube 26 and an expansion valve 27 to the refrigerating coil 28 located in the reservoir 15. From the coil 28, the refrigerant returns through a pipe 29 to the compressor 22. Water from a water main 30 is led through a valve 31 into the refrigerant cooling line 32 which includes a coil 33 inside of the coil 24, and a drain pipe 34 which is connected to a sewer outlet. The coil 33 is a conventional cooling coil for removing heat of compression from the refrigerant 45 in the coil 24.

It may be noted at this point that the pump 18 will draw the water from the collecting pan 10 and deliver it to the reservoir 15. Because the spray impeller coil is a restricted outlet, a certain 50 amount of pressure will be built up in the air cushion space 19 by the pumping of the refrigerating water into the reservoir 15. This pressure will deliver the water through the pipe 20 to the outlet 12 from which it will be sprayed into an 55

air current for cooling and dehumidifying purposes. However, as the spray produced at the outlet 12 condenses moisture from the air being conditioned, the water in the system will commence to build up, and a point would be reached at which the float valve 11 would close off, and the pressure in the system between the pump 18 and the float valve 11 would build up to a point where some part of the system would have to give way.

The present invention provides a pressure tube 35 which connects the delivery line 20 to the drain line 34. In order that the relief tube 35 may not reduce the pressure in the delivery line 15 20 to such a low level as to prevent the delivery of water to the outlet 12, I provide an escape valve 36 adapted to remain closed under normal operating conditions and to open only when the pressure in the system rises above a predetermined point. The escape valve 36 thus serves to allow the elimination of excess moisture from the system when a predetermined pressure has been reached.

The pressure which is built up in the system 25 between the pump 18 and the outlet 12 is determined by the existence of a balance between the resistance of the outlet as varied by the position of the float valve 11, and the pressure head produced by the pump 18. In other words, the system 30 may be said to be one which requires a condition of substantial equilibrium in order to operate.

In order to determine and regulate the pressure in the system, I provide a throttling valve 38 35 which is disposed in the line 20 between the reservoir 15 and the connection 21 and pressure gauges 39 and 40 disposed on either side of the throttling valve 38 so that readings may be taken of the pressure drop through the throttling valve 40 38.

It will now be seen that by adjusting the throttling valve 38, the pressure in the relief tube 35 may be so correlated to the pressure at the float valve connection 21 that excess moisture may 45 be allowed to escape from the system without undue closing of the float valve 11. This will be understood when it is considered that the rate of flow through the outlet 12 (and consequently the rate of building up of the level in the pan 10) 50 will vary according to the pressure head at the valve connection 21. It may be noted further at this point that in installing the two units of a system of this kind, under various conditions of installation, the height of the unit A, relative to the unit B may vary within very broad 55 limits, and this height will in all cases be a factor in the determination of the pressure at the valve connection 21.

To trace the operation of the device from an inoperative condition to a moisture eliminating condition, it will be assumed that the water level in the pan A, before the operation of the system is started, is at the level indicated by the full line 41. The level in the reservoir 15 will be as indicated by the same type of full line 42. The system is then started up and the pump 18 will commence to take the water from the pan 10 and deliver it to the reservoir 15. For a period of say a minute, the pump will take the water out of the pan 10 faster than it is delivered to the outlet 12 until the head over the return opening 14 recedes to practically nothing, when the system runs in balance, generating a pressure of say twelve to fourteen pounds per square inch on the tank and discharge line, with the throttling valve

38 wide open. A substantial proportion of the water from the pan 10 is now in the reservoir 15. By manipulating the valve between the gauges 39 and 40 I thereupon establish a ratio of from say twenty pounds per square inch to six pounds per square inch, the twenty pounds pressure being on the relief tube 35, and the six pounds pressure being at the outlet 12. It is desirable to have from two to six pounds pressure on the outlet 12 to produce the proper volume spray and it is of course desirable that this head be maintained at a substantially constant predetermined level. The figures just given are merely illustrative and are not intended to limit the invention.

If no moisture were being added to the system, the respective levels in the pan 10 and reservoir 15 are now as indicated by the broken lines 45 and 44 respectively.

Assuming now that the system commences to condense moisture from the air being conditioned, the level in both the pan 10 and the reservoir 15 will rise to the level indicated by the dotted lines 43 and 46 respectively. As the level in the reservoir 15 is raised, the pressure in the air cushion space 19 will gradually build up until, when the levels 45 and 46 respectively are reached, this pressure will be sufficient to cause the pressure relief valve 36 to open and allow the excess moisture to escape into the drain pipe 34.

The air cushion in the reservoir 15 need not necessarily be as large as that illustrated. It is only necessary that the pressure which is built up within the reservoir be so predetermined and correlated with the pressure at which the relief valve 36 operates so that moisture will be eliminated from the system before the float valve 11 has reached such a level of closing as to seriously interfere with the flow of water through the outlet 12.

In addition to providing for disposal of excess water, the present invention provides for a more or less continuous dilution of circulated water, whereby impurities collected within the system may be gradually drained away.

It may be noted that best results are secured where the pump 18 is of a plunger type.

It is impossible for the pan 10 to overflow for the reason that the choke valve 21 will close off at the level 41. Should anything occur in the system which would cause the choke valve 21 to close off, the relief valve 36 will prevent any injury to the system from excessive pressures.

The pressure at which the valve 36 opens is higher than the pressure in the water line 32-34, in order that the escaping water may force its way into the drain.

It will be understood that the relief tube 35 may be connected to other drain outlets besides the cooling line 32-34, the latter being a convenient means of disposal.

I claim:

1. In an air conditioning system, the combination of conditioning mechanism operated by cold water and refrigerating mechanism including a refrigerating reservoir and a pump to pull water from the conditioning mechanism and to deliver it into the refrigerating reservoir, so as to build up pressure therein, a pipe line for cooling the refrigerant in the refrigerating mechanism, said pipe line being connected to a waste water outlet, a delivery line for delivering refrigerated water from the refrigerating reservoir to the conditioning mechanism, a return pipe line leading from the conditioning mechanism back to the refrigerating mechanism, means to collect condensate from said conditioning mechanism and to feed

such condensate into said return line at the region of collection and a relief by-pass connection between the said cooling line and the delivery line, said connection including an escape valve adapted to open at a predetermined pressure in the delivery line.

2. In an air conditioning system, the combination of conditioning mechanism operated by cold water and refrigerating mechanism including a refrigerating reservoir and a pump to pull water from the conditioning mechanism and to deliver it into the refrigerating reservoir, so as to build up pressure therein, a pipe line for cooling the refrigerant in the refrigerating mechanism, said pipe line being connected to a waste water outlet, a delivery line for delivering refrigerated water from the refrigerating reservoir to the conditioning mechanism, a return pipe line leading from the conditioning mechanism back to the refrigerating mechanism, means to collect condensate from said conditioning mechanism and to feed such condensate into said return line at the region of collection and a relief by-pass connection between the said cooling line and the refrigerating reservoir, said connection including an escape valve adapted to open at a predetermined pressure in the refrigerating reservoir.

3. Air conditioning apparatus comprising a refrigerating mechanism provided with a water cooling system for the compressed refrigerant, an air cooling apparatus adapted to be operated by cold water and provided with a condensate receiver into which is condensed the moisture from the air cooled thereby, means for cooling water

by said refrigerating mechanism, supply and return conduit connections between said cooling means and the air cooling apparatus, the condensate from the cooled air being fed into the return conduit connection with the returned water, and means for forcing the condensate from said cooling means into the water cooling system to be discharged with the water therein. 5

4. An air conditioning apparatus comprising a refrigerating mechanism including a water cooled condenser, means to cool water by said mechanism, an air cooling device located some distance from said mechanism, means to circulate cold water from said means to the air cooling device and to circulate return water and condensate 10 from the cooled air from the air cooling device to the water cooling means, and power means for ejecting from the apparatus with the water from said condenser an amount of water equivalent to said condensate. 15

5. An air conditioning apparatus comprising a power-driven refrigerating mechanism, means to cool water by said mechanism, a device some distance from said mechanism arranged to cool air and provided with means for receiving moisture condensed from the air cooled thereby, power means to circulate water from said water cooling means to the air cooling means and to circulate return water and condensate from the air cooling device to the water cooling means, and means actuated by said power means for ejecting from the apparatus an amount of water equivalent to said condensate. 20 25 30
